UNITED STATES PATENT OFFICE.

FRANK G. HOGLAND, OF CHICAGO, ILLINOIS, ASSIGNOR TO ILLINOIS SEWING MACHINE COMPANY, OF CHICAGO, ILLINOIS, A CORPORATION OF ILLINOIS.

DESIGN FOR A SEWING-MACHINE TABLE.

SPECIFICATION forming part of Design No. 36,032, dated August 26, 1902.

Application filed July 1, 1902. Serial No. 114,023. Term of patent 7 years.

To all whom it may concern:

Be it known that I, FRANK G. HOGLAND, a citizen of the United States of America, residing at Chicago, in the county of Cook and State of Illinois, have invented and produced a new, original, and ornamental Design for Sewing-Machine Tables; and I do hereby declare the following to be a full, clear, and exact description of the same, reference being had to the accompanying drawings, forming a part thereof.

In the drawings, Figure 1 is a perspective view, and Fig. 2 a rear elevation, of my new design for sewing-machine tables.

The sewing-machine table comprises the top A, having its front edge rectilinear and the end portions thereof curved, as shown, the frame B, having its front edge rectilinear and substantially parallel with the front edge of the top A, cover C, having its front edge rectilinear and parallel with the front edge of the frame B, horizontal drawer-supports

D, drawers E, having their ends and outer sides curved to coincide substantially with the corresponding end portions of the top A, 25 vertical door-posts F, ogee-curved in transverse section, doors G, having ogee curves H formed in their lower ends and ornamented with plain beading I, coinciding with such ogee curves, and the carved ornamentation 30 J, with which the inner ends of the beading I meet and coalesce.

Having described my invention, what I claim as new, and desire to secure by Letters Patent, is—

The ornamental design for a sewing-machine table herein shown and described.

In testimony whereof I have signed my name to this specification in the presence of two subscribing witnesses.

FRANK G. HOGLAND.

Witnesses:

L. L. MORRISON,
NELLIE BUNKER.
